UNITED STATES PATENT OFFICE.

DAVID STONE, OF NEW YORK, N. Y.

DESIGN FOR A SHAWL OR BREAST PIN.

SPECIFICATION forming part of Design No. 16,221, dated September 1, 1885.

Application filed June 24, 1885. Term of patent 7 years.

To all whom it may concern:

Be it known that I, DAVID STONE, of the city, county, and State of New York, have invented a new and original Design for Shawl or 5 Breast Pins and other Articles of Jewelry, of which the following is a full, clear, and exact description.

Reference is to be had to the accompanying drawings, forming a part of this specification, 10 in which—

Figure 1 is a plan view of a shawl-pin to which my new design has been applied, and Fig. 2 is a side elevation of the same, these 15 two views being deemed necessary to fully illustrate my design.

The leading feature of my design consists in a series of irregular continuous serpentine projections having a top surface resembling wound wire.

20 The article to which my design is applied may be rectangular, as shown in Fig. 1, or of any other desired shape, and upon the surface of the said article is formed a series of irregular continuous serpentine projections extending 25 from edge to edge of the article, as shown in Figs. 1 and 2. The top surface of the irregular continuous serpentine projections is roughened, giving to the said surface the ap-

pearance of a wire wound around another wire. 30

The series of irregular continuous serpentine projections can be arranged diagonally upon the surface of the article, as illustrated in Fig. 1, or transversely or longitudinally, as may be desired, the design in all cases being 35 the same.

I am aware of a prior patented design in which the surface of the article was formed in imitation of crape—that is, with broken serpentine projections or serpentine projections 40 of different lengths, in contradistinction to continuous serpentine projections—and I do not claim such as of my invention.

I claim—

The design for a shawl or breast pin or 45 other article of jewelry herein shown and described, the same consisting of a series of irregular serpentine projections continuous across the face of the pin or other article, the said projections having their top surfaces orna- 50 mented to resemble twisted wire.

DAVID STONE.
